No. 806,238.

PATENTED DEC. 5, 1905.

W. L. AURAND.
GRAIN DOOR FOR CARS.
APPLICATION FILED APR. 5, 1905.

UNITED STATES PATENT OFFICE.

WILLIAM L. AURAND, OF MILFORD, ILLINOIS.

GRAIN-DOOR FOR CARS.

No. 806,233.

Specification of Letters Patent.

Patented Dec. 5, 1905.

Application filed April 5, 1905. Serial No. 253,970.

To all whom it may concern:

Be it known that I, WILLIAM L. AURAND, a citizen of the United States, residing at Milford, in the county of Iroquois and State of Illinois, have invented a new and useful 5 Grain-Door for Cars, of which the following is a specification.

This invention relates to inside doors or grain-doors for freight-cars, and has for its 10 object to simplify the mounting of such doors whereby they may be run up to the top of the car when not in use and conveniently drawn down and locked when required for use.

15 It is furthermore designed to provide for preventing the doors from working loose under the jarring movements of the car and at the same time to facilitate releasing and elevating the doors while unloading the car.

20 Another object of the invention is to permit outward swinging or tilting of the lower end of the door to permit of the grain being discharged beneath the lower edge of the door.

25 With these and other objects in view the present invention consists in the combination and arrangement of parts, as will be herein-after more fully described, shown in the accompanying drawings, and particularly 30 pointed out in the appended claims, it being understood that changes in the form, proportion, size, and minor details may be made within the scope of the claims without departing from the spirit or sacrificing any of 35 the advantages of the invention.

In the accompanying drawings, Figure 1 is a side elevation of a portion of a freight-car, showing the doors of the present invention mounted thereon. Fig. 2 is a vertical sectional view taken transversely through the doors. Fig. 3 is a horizontal sectional view on the line 3 3 of Fig. 1. Fig. 4 is a detail view of one of the guideways for the door. Fig. 5 is a detail cross-sectional view of the 45 guideway. Fig. 6 is a fragmentary view of one of the lower corners of the door. Fig. 7 is a detail perspective view of a terminal of one of the supporting-bars at the tops of the door-sections. Fig. 8 is a fragmentary perspective view of one of the keeper-plates.

Like characters of reference designate corresponding parts in each and every figure of the drawings.

In disclosing the present invention a portion 55 of an ordinary type of freight-car has been shown at 1 in the drawings, said car be-

ing provided with the usual side doorway 2, which is ordinarily closed by an outside sliding door, the latter not being shown in the drawings. In carrying out the present invention an upright guideway 3 is connected to each door-post 4, as best illustrated in Fig. 2 of the drawings. This guideway is in the nature of a channel-bar having the inner faces of its sides undercut to form a dovetailed guideway, as best shown in Fig. 5 of the drawings, and the guideway is held in place by means of fastenings 5, such as screws. The upper end of the guideway is enlarged, as at 6, to form a pocket, and other 70 smaller pockets 7 and 8 are formed at about the middle and adjacent the lower end of the guideway, each of the latter pockets being segmental in shape and projected entirely at the front of the guideway. As best indicated in Fig. 2 of the drawings, it will be noted that the guideways are let into the door-posts so as to be flush with the inner corners thereof, and the lower ends of the guideways extend downwardly slightly more 75 than one-half of the height of the doorway.

The present door is made in upper and lower sections, (designated 9 and 10,) each section being provided at its upper end with a cross-bar 11, which is secured across the front 85 face of the door and is provided with enlarged, dovetailed terminals 12, preferably conical in shape, to work in the guideways and capable of being received within the respective seats or pockets 7 and 8 when the 90 sections are closed and in use. When the door is closed, the lower edge of the lower section 10 rests upon the floor of the car, while the lower edge of the upper section rests upon the top edge of the lower section and is 95 provided with a plate or strip 13, secured to the back of the upper section and lapping the joint of the two door-sections, so as to close said joint and prevent the escape of grain 100 therefrom.

When the grain-door is not in use, the upper section is lifted slightly and then moved rearwardly, so as to move the heads or terminals of the bar 11 out of the seats 7 in the guideways 3, whereupon the door is lifted 105 until the ends of the bar come into the upper pockets 6, and then the lower edge of the door is swung upwardly and inwardly and each free corner engaged with a keeper or clip 14, loosely hung from the top of the car, 110 thereby to hold the door-section in an overhead position when not required for use.

After the upper section has thus been supported in an elevated position the lower section is run up in the same manner and supported in its elevated position by means of a pendent clip or bracket 15, similar to the bracket 14.

It will here be explained that when the door-sections are in use they are held against substantially upward displacement by the 10 tops of the seats 7 and 8, and the bottoms of these seats are dropped or depressed below the passages between the seats and the guideway, so as to prevent inward movement of the ends of the bars 11 in the guideways. In 15 other words, it is necessary to first lift the doors and then force them rearwardly or inwardly to bring the bars into the guideways.

The means for locking the lower free end of the lower door-section when in use consists of a cross-bar 16, disposed across the front of the lower portion of the bar and mounted for vertical movement in a pair of loops or brackets 17, embracing the end portions of the bar and secured to the front of 20 the door-section. These brackets are located inwardly from the upright edges of the door, and the locking-bar 16 extends substantially to the upright edges of the door, said ends of the bar being dropped or depressed, 25 as at 18, so as to come down close to the bottom edge of the door and engage sockets or keepers 19, secured to the bottom of the car and against the respective door-posts, whereby the door is held against swinging movements both inwardly and outwardly. Upon 30 the top of the bar are upstanding projections or shoulders 20, which overlap the tops of the respective brackets 17 at the inner sides thereof, so as to prevent endwise displacement of the bar from the brackets without interfering with the elevation of the bar. To release the door, the locking-bar 16 is elevated until its depressed ends 18 clear the tops of the seats or sockets 19, whereupon 35 the door may be swung inwardly, and in order that the door may be swung outwardly its lower corners are cut away obliquely, as at 21, so as to swing across the tops of the keepers without interference thereby.

40 In addition to the locking-bar 16 there is another locking-bar 22, located above and parallel with the bar 16 and connected thereto by a pair of upright cross-bars 23, the end portions of the bar 22 being received within 45 the loops or brackets 24, similar to the brackets 17, and the extremities of the bar 22 being received within keepers 25, carried by the respective door-posts. As best indicated in Fig. 8 of the drawings, it will be noted that 50 each set of keepers 19 and 25 is carried by a metallic plate or bar 26, which is secured to the adjacent door-post, the keeper 25 being substantially L-shaped to support the ends of the bar 22. As shown in Fig. 6, it will be 55 noted that each upright edge of the lower door

10 is notched or cut away, so as to pass by the adjacent keeper 25 when the door is swung outwardly.

By reference to Figs. 2 and 3 of the drawings it will be noted that each door is provided upon its rear side and at each upright edge with a hinged flap 28, which is capable of being folded against the adjacent door-post when the door is closed, so as to effectually close the joint between the door and the door-post and in particular to close the joints produced by the cut-away portions 21 and 27 of the lower door. When the doors are folded up against the top of the car, the flaps 28 are of course folded inwardly across 80 the backs of the doors.

It will here be explained that the upper terminal pocket 6 of each guideway 3 is offset rearwardly and located above the top of the doorway, whereby when the doors are swung 85 upwardly and supported in the clips 14 and 15 said doors lie entirely above the upper edge of the doorway, and therefore do not obstruct the doorway.

Having fully described the invention, what 90 is claimed is—

1. The combination with a freight-car having a side doorway, of a grain-door mounted to swing in and out upon a horizontal axis, keepers provided upon the car in front of the door, and a horizontally-disposed locking-bar mounted upon the door for vertical movement with its ends formed for engagement with the keepers to lock the door, the edge of the door being cut away in alignment with 100 the keepers to swing forwardly past the same when the locking-bar is disengaged from the keepers, the locking-bar being spaced above and lying adjacent the floor of the car to receive a pry-bar beneath the locking-bar and 105 against the floor of the car as a fulcrum-support.

2. The combination with a freight-car having a side doorway, of a door mounted to swing upon a horizontal axis, keepers secured in the lower corners of the doorway in front of the door, and a vertically-movable horizontally-disposed locking-bar carried by the front of the door with its ends formed for engagement with the keepers, the lower corners of the door being cut away to swing forwardly across the tops of the keepers when the locking-bar has been elevated out of engagement with said keepers, the locking-bar being spaced above and located adjacent the 110 floor of the car to receive a pry-bar beneath the locking-bar and against the floor as a fulcrum-support.

3. The combination with a freight-car having a side doorway, of a door mounted to 115 swing upon a horizontal axis, keepers located in the lower corners of the doorway, the lower corners of the door being cut away to swing across the tops of the keepers, opposite brackets carried by the front of the door, and a 120

substantially horizontal locking-bar engaging said brackets and movable vertically thereon, the ends of the locking-bar being downwardly offset for engagement with the 5 respective keepers and closing the joints between the tops of the keepers and the cut-away corners of the door, the locking-bar being spaced above and adjacent the floor to receive a pry-bar beneath the locking-bar and against the floor as a fulcrum-support.

4. The combination with a freight-car having a side doorway, of upright guideways upon the door-posts and provided with corresponding upper and lower laterally-extended 15 seats, and upper and lower door-sections having guide projections working in the guideways and normally received within the corresponding seats from which the door-sections hang when the door is closed.

5. The combination with a freight-car having a side doorway, of upright guideways upon the door-posts and provided with corresponding upper and lower laterally-extended seats, and upper and lower door-sections having 25 guide projections working in the guideways and normally received within the corresponding seats from which the door-sections hang when the door is closed, the lower section being independent of the upper section 30 and capable of having its lower end swung outwardly upon its guide projections as supports.

6. The combination with a freight-car having a side doorway, of upright guideways 35 carried by the guide-posts and provided at

their upper ends with laterally-enlarged pockets, said guideways being provided with corresponding upper and lower seats projected at one side thereof, independent upper and lower door-sections having guide projections working in the guideway and received within the corresponding seats from which the door-sections hang when closed, each section capable of being slid upwardly in the guideway to bring its projections into the pockets and then swung upwardly against the top of the car, and means carried by the top of the car for detachably supporting the door-sections when elevated.

7. The combination with a freight-car having a side doorway, of a grain-door mounted to swing in and out upon a horizontal axis, plates secured to the door-posts and carrying the upper and lower keepers projected across the front of the door, upper and lower connected substantially horizontal locking-bars mounted upon the door for vertical movement with their ends formed for engagement with the keepers to lock the door, the upright edges of the door being cut away in 50 alignment with the keepers to swing forwardly past the same when the locking-bars are disengaged from the keepers.

In testimony that I claim the foregoing as my own I have hereto affixed my signature in 55 the presence of two witnesses.

WILLIAM L. AURAND.
